UNITED STATES PATENT OFFICE.

JEAN BAPTISTE GUSTAVE ADOLPHE CANET, OF PARIS, FRANCE, ASSIGNOR OF ONE-HALF TO THE SIR JOSEPH WHITWORTH & COMPANY, LIMITED, OF MANCHESTER, ENGLAND.

CARRIAGE FOR QUICK-FIRING GUNS.

SPECIFICATION forming part of Letters Patent No. 499,516, dated June 13, 1893.

Application filed December 8, 1892. Serial No. 454,502. (No model.) Patented in France December 31, 1887, No. 187,908, and in England February 11, 1888, No. 2,075.

To all whom it may concern:

Be it known that I, JEAN BAPTISTE GUSTAVE ADOLPHE CANET, engineer, a citizen of the Republic of France, and a resident of Paris, France, have invented certain new and useful Improvements in Carriages for Quick-Firing Guns, (for which I have obtained patents in Great Britain, No. 2,075, dated February 11, 1888, and in France, No. 187,908, dated December 31, 1887,) of which the following is a specification, reference being had to the accompanying drawings.

This invention relates to improvements in carriages for quick-firing guns.

15 In the accompanying drawings which illustrate the said invention, Figure 1 is a side elevation partly in central section of a gun carriage showing a portion of the gun mounted therein. Fig. 2 is a detail view of the 20 mechanism for effecting the vertical pointing of the gun. Fig. 3 is a transverse section, and Fig. 4 is a longitudinal section on the line x, x Fig. 3, showing a modified form of the brake cylinder. Fig. 5 is a horizontal section 25 through the mechanism shown in Fig. 2 drawn to an enlarged scale. Fig. 6 is a sectional plan of the recuperator apparatus, and Fig. 7 is partly an end view and partly a transverse vertical section of the gun mounting.

30 Like letters indicate corresponding parts in all the figures.

A is the gun.

B is the frame of the carriage which is supported upon a pivot plate C in any ordinary 35 or usual manner.

D is a hydraulic cylinder or jacket which surrounds the gun and which is supported by trunnions D' or otherwise in the frame B. The said cylinder or jacket D which constitutes the brake cylinder is closed at the ends by glands D''. The brake cylinder is filled 40 with liquid.

E is a collar formed on the gun and arranged to be inclosed by the cylinder D and form the brake piston. The said piston is made to have a little clearance in the cylinder D so that liquid can pass from one side thereof to the other. The external diameter of

the gun is made larger in front of the piston E than behind the said piston. Consequently 50 the volume of the annular chamber between the gun and the cylinder D is greater when the gun is run out than when it is run in.

In the modified form of brake cylinder shown in Figs. 3 and 4, the piston E which fits freely in the cylinder is provided with one or more longitudinal grooves E' in its periphery. Projecting into each said groove E' is a rib or strip E'' which is fixed in the brake cylinder. When the gun recoils the liquid 60 passes from one side of the piston to the other through the spaces between the bottom of the grooves E' and the faces of the strips E'' and as the strips are made of variable depth from end to end, the size of the thoroughfare 65 for the passage of the liquid varies at each part of the recoil and consequently the resistance to recoil is varied.

F is a recuperator cylinder fitted with a piston G.

II is a rod attached to the piston at one end and arranged at its other end to slide through a supporting bracket I which is suitably connected with the gun carriage as hereinafter described.

K K are recuperator springs threaded on the rod H and bearing at one end against the piston G and at the other end against a transverse bar L which is attached by side rods L' to the cylinder D.

D'' is a thoroughfare leading from the front of the brake cylinder D to the recuperator cylinder F.

D' is a non-return valve placed in the thoroughfare D''. The said valve is arranged 85 to open toward the cylinder F so as to allow the liquid to flow from the brake cylinder into the recuperator cylinder. The said valve is maintained on its seat except during recoil by a spring D''. A small orifice D'' is formed 90 in the valve to allow the liquid to flow back again into the brake cylinder. In some cases the valve D' is dispensed with.

The action of this apparatus is as follows: When the gun recoils, the liquid displaced 95 from the brake cylinder by the part of the

gun in front of the collar E raises the valve D⁴ from its seat and enters the cylinder F and forces backward the piston G thus compressing the recuperator springs K, K. The 5 energy which is thus stored up in the springs K, K during recoil, serves to slowly run out the gun again after the recoil is spent by forcing the liquid back through the small orifice D⁶ in the valve D⁴ into the brake cylinder. In lieu of the springs K, K I may 10 employ a suitable fluid which is upon recoil put under pressure by the movement of the recuperator piston.

For effecting the vertical pointing of the 15 gun, I provide as follows—that is to say: I fix to the frame B on each side of the gun a bracket M, and I provide a ring N through which the gun is capable of sliding. On each 20 side of the ring N I fix a sector O in which is formed a curved groove or slot O' struck from the same center as the trunnions of the gun. The sector O on the left side of the gun is toothed. At the rear extremity of each 25 bracket M I form or fix thereto a block M' which is adapted to work in or engage with the slot O' and prevent to and fro sliding movement of the ring N while allowing the said ring to rise and fall as the gun is turned about its trunnions. I fix the back sight N² on the ring N. 30 By this arrangement the gunner is enabled to keep his eye along the line of sight during recoil. In bearings on the bracket M at the left side of the gun I mount a shaft P on which is fixed a worm or endless screw P' 35 and a hand-wheel Q for turning the same.

R is a worm wheel carried by the bracket and gearing with the said worm P'. On the axle of the worm wheel is fixed a pinion R' which gears with the adjacent toothed sector 40 O. By rotating the hand wheel Q the gun can be turned about its trunnions to effect the vertical pointing. The lateral training of the gun is effected by pushing the shaft P to the right or to the left as required.

What I claim is—

1. The combination of the gun A provided with the collar E forming the brake piston, the gun being of larger diameter in front of the said collar than behind it, a brake cylinder D inclosing the collar E and through 50 which the gun can slide, said cylinder being supported by the gun-carriage, and a recuperator device communicating with the brake cylinder by a passage D³ substantially as described, and for the purpose specified. 55

2. The combination of the gun A provided with a collar E forming the brake piston, the gun being of larger diameter in front of the said collar than behind it, a brake cylinder D inclosing the collar E and through which 60 the gun can slide, said cylinder being supported by the gun carriage, a recuperator cylinder F communicating with the brake cylinder by a passage D³ in which is placed a valve D⁴ opening from the brake cylinder, a small hole 65 being provided in the valve to permit the return of the liquid to the brake cylinder, a piston G working in the cylinder F, and recuperator springs K K acting on the said piston, substantially as, and for the purpose, specified. 70

3. The combination, with the gun A and the carriage B, of a ring N which carries the back sight and through which the gun can slide, sectors O, O fixed to the said ring, segmental circular grooves O' O' formed in the 75 said sectors and having the same centers as the trunnions, curved slide blocks fixed to the carriage and engaging the said grooves, and means for effecting the vertical pointing of the gun substantially as, and for the purpose, specified. 80

In testimony whereof I have hereunto signed my name in the presence of two subscribing witnesses.

JEAN BAPTISTE GUSTAVE ADOLPHE CANET.
